UNITED STATES PATENT OFFICE

102,846

DESIGN FOR AN ELASTIC FABRIC

Raymond K. Siner, Wyomissing Hills, Pa., assignor to The Narrow Fabric Company, West Reading, Pa., a corporation of Pennsylvania

Application November 21, 1936, Serial No. 66,062

Term of patent 7 years

To all whom it may concern:

Be it known that I, Raymond K. Siner, a citizen of the United States of America, residing at Wyomissing Hills, in the county of Berks and State of Pennsylvania, have invented a new, original, and ornamental Design for an Elastic Fabric, of which the following is a specification, reference being had to the accompanying drawing, forming part thereof.

Figure 1 discloses a portion of elastic fabric embodying my ornamental design, to which no tension is applied.

Fig. 2 discloses a portion of the elastic fabric depicted in Fig. 1, as it appears when subjected to tension substantially equivalent to that incident to normal use.

Fig. 3 shows the reverse side of the fabric depicted in Fig. 1, and more particularly illustrates the appearance of the edge portions on the reverse side of the fabric.

The figures disclose the elastic fabric enlarged to approximately one and one-half times normal size, so that they will be approximately full size upon the reduction of the same to the ultimate size as appearing in the patent copy.

I claim.

The ornamental design for an elastic fabric as shown and described.

RAYMOND K. SINER.
